UNITED STATES PATENT OFFICE.

SAMUEL S. PETTICORD, OF WHEELING, WEST VIRGINIA.

RADIATOR.

1,209,486.

Specification of Letters Patent. Patented Dec. 19, 1916.

Application filed September 9, 1914. Serial No. 860,864.

To all whom it may concern:

Be it known that I, SAMUEL S. PETTICORD, a citizen of the United States, residing at Wheeling, in the county of Ohio and State of West Virginia, have invented certain new and useful Improvements in Radiators; and I do hereby declare the following to be a full, clear, and exact description of the invention, such as will enable others skilled in the art to which it appertains to make and use the same.

This invention relates to radiators, and more particularly to a device of this character especially designed for cooling the water circulated about the cylinders of the engine of a motor vehicle.

An object of the invention is the provision of a radiator embodying a plurality of water tubes arranged in columns and sections of screen removably positioned between the tubes whereby access may be readily had to the tubes.

With these and other objects in view, the invention consists in the novel construction, arrangement and formation of parts as will be hereinafter specifically described, claimed and illustrated in the accompanying drawings, in which:

Figure 1 represents a front elevation of the radiator complete. Fig. 2 represents a front elevation of the water tubes and burner. Fig. 3 represents a horizontal sectional view on the line 3—3 of Fig. 1. Fig. 4 represents a vertical sectional view on the line 4—4 of Fig. 1. Fig. 5 represents an enlarged detail view, partly broken away, of the burner detached from the radiator. Fig. 6 represents an enlarged detail side elevation of the lower portion of the radiator, deflector plate and operating means therefor. Fig. 7 represents an enlarged sectional detail view of the upper portion or dome of the radiator. Fig. 8 represents a perspective view of one of the gaskets removed.

Referring to the drawing in detail, wherein similar reference numerals indicate corresponding parts throughout the several views, the numeral 10 indicates a plurality of water tubes arranged in a plurality of columns or rows and secured at their upper extremities in apertures formed in the top plate 11 and secured at their lower extremities in apertures formed in the bottom plate 12. Gaskets 13 formed of rubber, or other suitable material, are arranged above and below the top and bottom plates 11 and 12

respectively. A dome or cover 14 is arranged over the top gasket 13 and is provided with an inwardly directed flange 15 formed with a plurality of apertures aligning with the apertures formed in the gasket 13 and in the head portions of the top plate 11, receiving bolts, or equivalent means, for securing the cover 14 in position over the top plate 11. The chamber 16 formed by the cover 14 and top plate 11 communicates with the upper open ends of the water tubes 10, and an inlet pipe 17 is secured in the rear wall of the cover 14 and is adapted to be connected with the water jacket of the cylinders of the engine. A bottom 18 is arranged under the bottom plate 12 and is provided with an inwardly directed flange 19 secured to the outer edges of the plate 12. An outlet pipe 20 is secured in the rear wall of the bottom 18 and establishes communication between the lower chamber 21 and the water jackets of the cylinders of the engine.

A deflector plate 22 is pivotally connected as by hinges 23 to the lower front edge of the bottom 18, and is adapted to be operated by a flexible connection 24 connected at 25 to one end thereof. The connection 24 is preferably extended over a pulley 24^a to a point conveniently near the driver of the vehicle.

An end wall 25 is permanently secured between the top and bottom plates 11 and 12 respectively, and an opposite end wall 26 is removably secured between the opposite ends of said top and bottom plates. The end wall 26 is removably secured in position by engaging the lower edge thereof behind the heads 26^a of the bolts securing the bottom plate 12 to the bottom 18 and securing the upper portion thereof in position by a nut 25^a fitted upon a screw threaded shank 26^b projecting longitudinally of the top plate 11 and positioned through an aperture formed in the end wall 25. A screen section 27 is permanently secured between the top and bottom plates 11 and 12 adjacent their rear longitudinal edges, and a plurality of removable screen sections 28 are slidably mounted between the rows of pipes or tubes 10. The screen sections 28 are secured against removal by the removable end wall 26.

A burner 29 is positioned centrally on top of the bottom plate 12 between two of the removable screen sections and is adapted to be fed with a gaseous fuel through a pipe

30. A casing 31 of asbestos is positioned around the burner 29 and extends upwardly a distance within the radiator.

The top of the cover 14 is provided with 5 a flanged opening 32 through which the radiator is filled with water and the opening 32 is adapted to be closed by a suitable cap 33 communicating with the interior of the radiator permitting the escape of steam 10 generated therein. The upper end 34 of the cap 33 is of hollow globular formation and is provided with an aperture 35 in the upper end thereof. A spider or the like 36 is positioned within the cap 33 below the 15 globular portion 34, and a stem 37 is secured in vertical position in said spider. A valve 38 is slidably mounted on the rod or stem 37 and is adapted to be moved upwardly into contact with the inner face of 20 the globular portion 34 to prevent the escape of water from the radiator. The steam generated by the heat of the engine may readily pass around the valve 38 without raising the same, but the force of the 25 water rising within the cap firmly seats said valve and prevents such water from escaping.

In use, the heated water from the water jacket of the engine (not shown) enters 30 the radiator through the inlet pipe 17 and flows downwardly through the chamber 15, pipes 10, bottom chamber 21 and out through the outlet pipe 20. By adjusting the deflector plate 22 in the position illustrated in Figs. 4 and 6, air passing under 35 the radiator is deflected upwardly against the water tubes 10 and screen sections 27 and 28, thus materially assisting in cooling the water flowing through the radiator.

Should any of the pipes become broken or 40 detached it is clearly apparent, from the foregoing, that the same may be quickly and conveniently repaired by removing the screen sections 28, and, if necessary, the cover 14 and bottom 18. In cold weather, 45 when it is difficult to start the engine, the burner 29 may be lighted, thus heating the adjacent screen sections 28 and the water standing in the water pipes 10 and causing it to circulate about the water jackets of the 50 cylinders of the engine, and quickly and effectively warming the engine. The removable screen sections 28 materially assist in radiating heat from the burner 29 and consequently accelerate heating the water 55 standing in the tubes 10.

What I claim is:

A radiator comprising a pair of plates arranged one above the other, an end wall 60 permanently secured to said plates, a plurality of water tubes arranged in rows and connecting said plates, hollow members arranged above and below said plates and communicating with said water tubes, a removable end wall engaged between said plates 65 and arranged in spaced relation to the first-mentioned end wall, and screen sections removably positioned between the rows of tubes and secured against removal by the relatively stationary and removable end 70 walls.

In testimony whereof I affix my signature in presence of two witnesses.

SAMUEL S. PETTICORD.
